DESIGN.

—o—
G. G. WOLFE.

STOVE TOP ORNAMENT.

No. 17,208.

Patented Mar. 22, 1887.

UNITED STATES PATENT OFFICE.

GURDON G. WOLFE, OF TROY, NEW YORK, ASSIGNOR TO THE FULLER & WARREN COMPANY, OF SAME PLACE.

DESIGN FOR A STOVE-TOP ORNAMENT.

SPECIFICATION forming part of Design No. 17,208, dated March 22, 1887.

Application filed February 10, 1887. Serial No. 227,221. Term of patent 7 years.

To all whom it may concern:

Be it known that I, GURDON G. WOLFE, of the city of Troy, county of Rensselaer, State of New York, have invented a new and useful Design in Top Ornaments for Stoves, of which the following is a specification.

My design relates to the top ornaments of stoves, as the same is shown in the accompanying photograph, forming a part of this specification, in which the several parts of the ornament are designated by letters and the surface ornamentation by numbers, and as follows:

The letter P designates the pedestal, having the beveled molding 5, extending upwardly and inwardly, the filleted reversing ovolو molding 6, the plate molding 7, the upper reversing ovolو molding 8, and plate molding 9, and the base ovolو molding and band 10, all arranged in revolution upon the pedestal.

The letter U designates the urn-form cup of the ornament, arranged upon and above the pedestal P and around the column C, the latter passing up through the cup center; and the letters B designate brackets, which at their

lower ends form exteriorly-placed and radially-arranged grooves 4 for the cup exterior, and which, where extended above the edge of the latter, curve inwardly and upwardly in scroll formation for attachment to the pedestal, and

then curve therefrom downwardly and outwardly, having a terminal animal-head of newt delineation, 2. The interior face of these brackets, where over the cup interior, are convolutedly scrolled, as indicated at 3, and between

each two of these brackets, where extended 35 radially downward on the cup exterior, there is arranged a cherub figure, 11, with vermiciform ornamentation 12 between each of the cherub figures and the radially-arranged grooves.

The letter N designates a bulb having an 40 antique-bottle form, arranged on the column C where projecting up through the cup U, and R a button, also arranged upon said column above the radially-arranged heads on the brackets. Upon the column, above the button 45 R, is an ornament, H, having an inverted-bottle form, and above the latter the buttons 13 and the apex ornament 15.

Having thus described my design, what I claim, and desire to secure by Letters Patent, 50 is—

The design for a stove-top ornament, consisting of the pedestal P, the cup U, having the cherubic figures, the brackets B, surrounded by animal-heads in newt delineation, 55 the column C, with the bulb N and button R, and the inverted-bottle-shaped ornament, all having the shape and ornamentation as shown and described.

Signed at Troy, New York, this 7th day of 60 July, 1886, and in the presence of the two witnesses whose names were by them hereto written.

GURDON G. WOLFE.

Witnesses:

CHARLES S. BRINTNALL,
W. E. HAGAN.
